UNITED STATES PATENT OFFICE.

JOHN E. SEDERHOLM, OF ST. PAUL, MINNESOTA, ASSIGNOR TO AMERICAN HOIST & DERRICK COMPANY, OF ST. PAUL, MINNESOTA, A CORPORATION OF MINNESOTA.

ELECTRIC RIVET HEATER.

Application filed December 8, 1924. Serial No. 754,613.

This invention relates to new and useful improvements in electric rivet heaters particularly designed for use in heating rivets to be used in hot-riveting structural steel 5 frames for buildings, bridges, etc., and more particularly relates to such heaters adapted for heating rivets for use in the construction of steel boilers wherein the seams and joints must be securely riveted in order that the 10 boiler, when completed, will be leak-proof and safe.

Rivet heaters in use at the present time are usually so constructed as to direct a uniform flow of current through the entire 15 length of the rivet when heating it. By thus causing a uniform flow of current to flow through the rivet the small end of the rivet is usually heated to a higher temperature than the opposite or head end thereof caused 20 by the current carrying capacity of the small end of the rivet being relatively less than the head, and thereby offering a greater resistance to the flow of current therethrough. The above condition may also be intensified 25 as a result of the possibility of obtaining a relatively poorer electrical connection between the small end of the rivet and the heating element, than may be obtained between the head end and its respective heating 30 element, caused by the smaller end of the rivet sometimes being very rough and uneven, thereby making only a point contact with the heating element. Such heating of the rivet has been found unsatisfactory and 35 objectionable in certain classes of work, such, for instance as boiler making, where it is essential that all joints and seams be made steam and water tight. In the manufacture of steam boilers, the method most 40 commonly employed at present to render the boilers leak-proof, is to peen over the edges of the rivet heads with an air hammer or other device after the rivets have been headed over, thereby substantially uniting the 45 edges of the rivet heads with the boiler plate, with the result that a leak-proof joint will be obtained between the rivet and boiler plate. The above procedure is usually 50 necessary as a result of the fact that the body or grip of the rivet usually cools quicker than the end thereof which is to be headed over, caused by contacting with the cold walls of the rivet hole. Therefore when 55 the end of the rivet is headed over a head will be formed thereon before the body or

grip of the rivet has expanded sufficiently to completely fill the aperture in which it is seated. Thus when the end of a rivet is headed over and the body or grip thereof has not sufficiently expanded to completely 60 fill the rivet hole, there will be danger of leakage around the rivet, which must be eliminated by such means as peening over the head of the rivet, as above described, before a leak-proof joint can be obtained. It 65 will therefore be readily seen and understood that the above described method of rendering a boiler leak-proof is objectionable as it requires considerable labor with a resultant increase in the cost of manufac- 70 ture.

An object of the present invention is to provide an improved rivet heater so constructed and designed as to enable the operator to heat the body of the rivet forming the grip, to a relatively higher temperature than the end thereof which is to be headed over. By thus heating the body, or that portion of the rivet which passes through the plates and forms the grip, to a very high degree of temperature, and the small end thereof to a considerably lower temperature, the body or grip portion of the rivet will expand and completely fill the rivet hole as soon as pressure is brought to bear against 80 the end of the rivet in heading it over. Such expansion of the rivet body will occur substantially before the head begins to form on the end of the rivet with the result that a leak-proof joint will be provided between 85 the body of the rivet, and the walls of the aperture in which it is seated, thereby eliminating the necessity of having to peen over the rivet heads after the boiler has been riveted. The above method of riveting will 90 also greatly increase the strength of the riveted joint as the two members or plates will be firmly and securely held together, thereby eliminating all danger of the plates creeping or changing their relative position, 95 100 which is a well known occurrence when employing the present method of riveting wherein the entire rivet is heated by directing a uniform flow of current therethrough. The above difficulty is usually caused by 105 some of the rivets being loose as a result of the rivet bodies not expanding sufficiently to completely fill the apertures in which they are seated before the heads are formed on the ends thereof. Further, the rivet heater 110

is provided with means whereby the operator may conveniently vary the temperature at either end of the rivet as required, or if desired, only one end of the rivet may be heated. The apparatus is also readily adjustable to all sizes of standard rivets.

Another object of the invention, therefore, is to provide an improved rivet heater of simple construction which is capable of being operated to full capacity continuously and will be efficient and positive in performance.

Another object of the invention is to provide means for heating the grip or any selected portion of a rivet to a higher temperature than the other portions, said means adapted to induce two distinct electric heating currents, and to pass the currents lengthwise through a rivet, one entirely and one partially therethrough, so that the heating effects of the two separately generated currents are combined throughout a selected portion of the rivet to superheat that portion.

Other objects of the invention will appear from the following description and the accompanying drawings and will be pointed out in the annexed claims.

In the accompanying drawings there has been disclosed a structure designed to carry out the various objects of the invention but it is to be understood that the invention is not confined to the exact features shown as various changes may be made within the scope of the claims which follow.

In the accompanying drawings forming part of this specification,

Figure 1 is a view in front elevation of the improved rivet heater showing a rivet positioned between the movable contacts thereof;

Figure 2 is a side view of Figure 1;

Figure 3 is a sectional view on the line 3—3 of Figure 1 showing the novel construction of the secondary elements;

Figure 4 is a sectional view on the line 4—4 of Figure 3 showing the relative positions on the laminated core of the primary windings and secondary elements;

Figure 5 is a plan view of the apparatus showing the various controls;

Figure 6 is a sectional view on the line 6—6 of Figure 3 with the operating levers and foot pedals omitted, showing the preferred manner of mounting the horizontal contact blocks on the secondary elements;

Figure 7 is a wiring diagram of the apparatus showing the magnetic circuits generated in the iron core when the primary windings or coils are energized;

Figure 8 is a diagrammatic view showing the primary windings and secondary elements mounted on the magnetic core and also indicating the path of the induced current built up in the secondary elements

when the primary windings are energized and a rivet is interposed between the contacts thereof, and

Figure 9 is an enlarged view showing a rivet positioned to be headed over, the shaded portion indicating the grip of the rivet and the portion which is heated to the highest temperature; a rivet also being shown after having been headed over to show how the grip of the rivet will completely fill the rivet hole.

The novel rivet heater shown in the accompanying drawings is an improvement on the form of rivet heater shown in my pending application Serial #579,940, filed August 5, 1922. As here shown, the frame of this rivet heater preferably comprises the upright front legs 11 and similarly shaped rear legs 12 connected together at their bottoms by means of the cross members 13. Plates 14 and 15 are secured to the front and rear legs as shown in Figures 1, 2, 3 and 4, which plates function to securely connect the legs together, thereby providing a very rigid and substantial frame.

A magnetic core, preferably rectangular in shape and constructed of laminated sheet metal in the usual manner, is mounted in the upper portion of the frame and is securely clamped between the front and rear legs by means of tie bolts 16. As shown in Figure 5, the front and rear legs 11 and 12 are preferably of angle iron construction so that the ends of the magnetic core may be clamped between the right-angled walls thereof, thereby providing a very rigid support for the core. As shown in Figure 4, the magnetic core preferably comprises the upper and lower horizontal sections 17 and 18 and an intermediately-disposed section 19 preferably of larger cross section connected together at their ends by means of the upright sections 21. The upper and lower parallel longitudinal extending members of the magnetic core are provided with suitable primary windings or coils 22 and 23, respectively, as shown. These coils are preferably mounted adjacent each end of the core and are suitably insulated therefrom as is customary in devices of this kind. The construction of the magnetic core and the arrangement of the primary windings or coils thereon is such that when the coils are energized two distinct magnetic circuits will be built up in the magnetic core as indicated by the arrows in the wiring diagram, Figure 7.

An important feature of this invention resides in the novel construction of the secondary elements which are mounted in spaced parallel relation on the magnetic core and suitably insulated therefrom. As shown in Figure 3, each secondary element is preferably constructed of two members which will hereinafter be referred to as the outer

and the inner secondary element. As the two secondary elements and the movable contacts mounted thereon are similar in construction, it will be necessary to describe but 5 one of the secondary elements, and its associated parts, like parts being referred to by like numerals. The outer secondary element preferably comprises the upper and lower horizontal legs or portions 24 and 25, 10 connected together at the rear of the machine by means of the upright portion 26. The upper leg 24 is preferably provided with an elongated head 27 which functions to provide a contact face or surface 28 for 15 a sliding contact block 29 mounted thereon. Yieldable means are preferably provided for securing the contact block 29 in electrical contact with the contact face 28 of the secondary element. Such means preferably 20 comprises a pair of studs 30 which are secured to the head 27 of the element and outwardly project therefrom in spaced parallel relation through an elongated opening 31 provided in the block, and having a wheeled 25 carriage 32 mounted thereon which is yieldably held against the outer face of the contact block by means of suitable compression springs 33 and the nuts 34 received in threaded engagement on the ends of the 30 studs 30. The contact block 29 is also preferably provided with a longitudinal flange 35 on each side which functions to retain the contact block in true alignment with the head 27 when moved thereon. By means 35 of the yieldably mounted carriage 32 it will be seen that the contact block 29 will be held in direct contact with the face 28 of the head 27 of the secondary element, thereby providing a good electrical contact at all 40 times regardless of the position of the block thereon.

The inner secondary element 36 is preferably U-shaped in form and comprises the upper and lower spaced parallel legs 37 and 38. In the particular construction here 45 shown the lower legs 25 and 38 of the outer and inner secondary elements, respectively, are secured together, the two elements preferably being formed of an integral casting 50 as shown but with the inner element connected with the lower leg of the outer element only at its front portion. (See Fig. 8.) Thus a common return circuit is provided for the two elements corresponding to 55 the common return provided by the intermediate member 19 of the core. The inner and outer secondary elements are insulated from one another at all other points, (see Figs. 3 and 8) an air gap being formed by 60 sawing. It will be noted that the U-shaped members have a nested relation and that the two lower legs of the inner and outer elements are disposed at the outer side of the core while the two upper legs respectively 65 pass between the intermediate section 19 and

the outer members 17 and 18. This arrangement in conjunction with the coils 22-23, and their relation to the secondary elements, provides means for separately generating two heating currents and enables the same 70 respectively to pass a current lengthwise through a rivet in the same direction in one current from end to end, and the other from an intermediate point toward the end with the current having a common return through 75 the outermost legs of the secondary elements and one end of the rivet, whereby the heating effects are additive for, in the case, superheating the grip portion of the rivet. By this novel construction, the lower legs 25 80 and 38 of the two members will provide a continuous contact face 39 adapted to receive a similar contact block 41 movably mounted thereon and yieldably held in electrical contact therewith by means of a carriage similar 85 in construction to the one shown in connection with the upper contact block 29, and which will, therefore, be referred to by like numerals.

Referring to Figures 1 and 6, it will be 90 noted that the upper horizontal leg 37 of the inner or smaller secondary element 36 is provided with a head 42 upon which a relatively smaller contact block 43 is mounted. The means provided for securing the 95 contact block 43 to the head 42 is similar to that shown with reference to the upper and lower contact blocks 29 and 41 and will therefore be indicated by like numerals. A complementary contact member 44, preferably 100 having a plurality of contact faces 45, is also mounted upon the head 42 and is yieldably and pivotally secured thereto by means of a stud 46, spring 47 and a nut 48, the stud 46 being secured to the head as 105 shown. This contact member 44 cooperates with the contact block 43 to provide a dual contact for the rivet when interposed therebetween as shown on the left-hand side of Figures 1 and 6, and it also functions as an 110 abutment for the rivet when the movable block 43 is moved into electrical contact with the rivet, clearly shown in Figure 1. By means of the pivotal mounting of the contact member 44 and its plurality of contact 115 faces 45, the member may be rotated to present a clean contact for the rivet, should the contact being used become ineffective as a result of being pitted or worn from arcing, etc.

Means are provided whereby the upper contact blocks 29 may be conveniently actuated as when it is desired to position a rivet between the upper and lower contact blocks for heating. Each contact block 43 125 preferably has a forked bracket 49 secured to the upper end thereof to which the upper ends of a pair of L-shaped actuating bars 51 are pivotally connected. The lower ends of the actuating bars 51 are pivotally con- 130

connected to suitable operating pedals 52 pivotally mounted in brackets 53 secured to a supporting bar 54 having its ends suitably secured to the cross members 13 of the frame as shown in Figure 4. Coiled tension springs 55 have their lower ends connected to the operating pedals 52 and their upper ends adjustably secured to an angle bar 56 which is suitably secured to the frame of the machine. The springs 55 function to yieldably retain the foot pedals 52 in their raised position thereby tending to downwardly force the upper contact blocks 29 into contact with the rivets when interposed between these blocks and the lower contact blocks 41. When it is desired to interpose a rivet between the contact blocks 29 and 41, the upper contact block 29 will be raised by the operator downwardly moving the foot pedal connected thereto. As soon as pressure is released from the foot pedal, the upper block 29 will be downwardly moved into electrical contact with the rivet thereby closing the heating circuit which will hereinafter be described. The lower contact blocks 41 are provided with means whereby they may readily be adjusted to the proper position which is usually determined by the thickness of the elements to be riveted together or by the length of the grip portion of the rivet. The means provided for thus adjusting the positions of the lower contact blocks 41 preferably consists in the provision of suitable hand levers 57 which are preferably mounted on studs 58 provided on the lower horizontal leg portions 25 of the outer secondary elements as shown in Figures 2 and 3. Each lever is connected with its respective contact block by means of a link 59 having one end pivotally connected to the lever and the other similarly connected to the side of the contact block. The levers 57 are also provided with suitable latches 61 adapted to engage quadrants 62 mounted on the angle bar 56 of the frame, whereby the blocks may be conveniently and adjustably held in adjusted position.

The means provided for actuating the relatively smaller horizontally mounted contact blocks 43 preferably consists in the provision of a pair of opposed arms 63 which are pivotally mounted on the frame of the apparatus by means of pivots or bolts 64. These arms are connected to their respective contact blocks by means of brackets 65, as shown in Figures 1 and 6, so that when the arms are oscillated, the contact blocks will be actuated. An anti-friction roller 66 is preferably mounted in the upper forked end portion 67 of each arm 63 and these rollers are adapted to be engaged by suitable cams 68 mounted on the adjacent sides of the upper contact blocks 29. Each arm 63 is yieldably held in contact with the cam 68 by means of a spring 69 having one end

connected to the arm and the other end connected to the head 27 of the outer secondary element. Thus it will be seen, by reference to Figure 1, that when the upper contact blocks 29 are raised by means of the foot 70 pedals 52, the horizontally mounted contact blocks 43 will simultaneously be outwardly moved to the position shown on the right-hand side of Figure 1. When a rivet has been positioned upon the lower contact block 75 41, as indicated by the dotted lines, and the upper contact block 29 is lowered to the position on the left-hand side of the above figure, the horizontal contact block 43 will simultaneously be moved into contact with 80 the rivet by the action of the spring, thereby completing the two heating circuits which will subsequently be described. The oscillating arms 63 are preferably insulated from the machine frame. A convenient form of 85 insulating the arms from the frame is shown in Figure 2 wherein each arm is constructed of an upper and lower section having an insulating block 71 interposed therebetween. It is to be understood, of course, that one 90 of the sections will be insulated from the bolts 72 by such means as suitable insulating bushings and washers (not shown), mounted on the bolts so that current cannot pass from one section to the other through 95 the bolts 72.

Means are also provided whereby the horizontally mounted contact blocks 43 may be manually actuated should it be desired to obtain a better contact with the rivet. Such 100 means preferably consists in pivotally mounting a hand lever 73 over each contact block 43. These levers are mounted on suitable pins 74 secured to the heads 42 of the upper horizontal leg 37 of the inner secondary elements 36. A pin 75 is mounted in each contact block 43 and these pins upwardly extend therefrom through elongated apertures provided in the hand levers 73. Thus it will be seen that when the hand levers 73 are outwardly moved from the position shown on the left hand side of Figure 5 to that shown on the right hand side of the figure, the contact block 43 on the right hand side of the figure will be outwardly moved to the position shown in Figure 1 so that a rivet may be interposed between the upper and lower contact blocks 29 and 41, respectively.

The wiring diagram of this novel rivet heater is shown in Figure 7. As here shown the primary coils 22 and 23 are connected up in such a manner that a number of different heats may be obtained, and also that the entire length of the rivet may be heated to a substantially uniform temperature, or one end may be heated to a considerably higher temperature than the opposite. Such heating of the rivet is accomplished by the simple manipulation of suitable control switches provided for that purpose. Elec- 130

trical energy is supplied to the primary coils 22 and 23 by means of conductors 77 and 78 through a main line switch 79. The conductor 77 leads from the binding post 81 of the main line switch 79 to a terminal 82 on the upper primary coil 22 on the right hand side of Figure 7. The other primary coil 22 is connected to the conductor 77 by a wire 83. The lower primary coils 23 are similarly connected to the conductor 77 by means of wires 84 and 85. Thus it will be seen that one end of each of the primary coils will always be in electrical connection with the binding post 81 of the main line switch. The conductor 78 of the other side of the line connects the binding post 86 of the main line switch with the high heat post of a suitable heat control switch mechanism. As shown in Figure 7, this control switch mechanism preferably comprises a plurality of interlocking switches, preferably three, thereby providing a low heat switch 88, a medium heat switch 89 and a high heat switch 91. These switches are also indicated in Figure 1 and on the wiring diagram by the letters L, M, and H, representing the low, medium and high heats. These switches are electrically connected to the conductor 78 as shown. The low heat switch 88 is connected to the low heat terminals 92 of the lower primary coils by means of wires 93 and 94, the medium heat switch 89 is similarly connected to the medium heat terminals 95 of the lower coils by the wires 96 and 97; and the high heat switch 91 is connected to the high heat terminals 98 of the lower primary coils 23 by means of the wires 99 and 101. Thus it will be seen that by the provision of the control switches 88, 89 and 91, a number of different heats may be obtained. These switches control the flow of current through the inner or smaller secondary elements and therefore through the body or grip of the rivet as indicated by the arrows in Figure 8. The interlocking heat control switches shown in the wiring diagram, Figure 7, and also shown in Figure 1, are similar in construction to a control switch forming the subject matter of my pending application, Serial #729,807, filed August 2, 1924.

A similar heat control switch mechanism is provided for controlling the amperage flow through the upper primary coils 22. This switch is preferably provided with a similar number of control switches 103, 104, and 105 which are in electrical connection with the main line conductor 78 as shown. The low heat switch 103 is connected to the low heat terminals 106 of the upper primary coils 22 by wires 107 and 108, the switch 104 to the medium heat terminals 109 of the coils by the wires 111 and 112, and the switch 105 to the high heat terminals 113 of the primary coils 22 by means of the wires 114 and 115. By the provision of the heat con-

trol switches 103, 104 and 105 the flow of current in the upper primary coils 22 may be controlled, as desired, which in turn controls the flow of induced current in the larger or outer secondary elements, as indicated by the arrows in Figure 8. The wiring diagram shown in Figure 7 is arranged for a 220 volt, 60 cycle alternating current circuit, but it is to be understood, of course, that the primary coils may be connected in such a manner that the apparatus may be used for different voltages, such for instance, as 440 volts.

The operation of this novel rivet heater may be explained with reference to Figures 1, 7 and 8. Before placing any rivets between the contact blocks for heating, the main line switch 79 will be closed as shown in Figure 7, thereby electrically connecting one end of each primary coil with the main line conductor 77. One of the heat control switches of each pair of primary coils will then be closed as shown in this figure, thereby completing a circuit through each pair of coils. In Figure 7, the high heat control switch 105 controlling the flow of current through the upper primary coils 22 is shown in circuit-closing position, while the circuit through the lower primary coils 23 is shown completed by the closing of the low heat switch 88. When the switches have been closed, as above described, the circuit through the upper primary coils will be as follows: from the main line switch 79 through the conductor 77, to the end terminal 82 of the primary coil on the right-hand side of Figure 7, through a portion of the winding of the coil to the high heat terminal 113, thence through the wires 115 and 114 through the switch 105, conductor 78, and back to the main switch terminal 86, thereby completing the circuit. The other primary coil 22 will also be energized as a result of having one end thereof connected to the conductor 77 by the wire 83 while the high heat terminal 113 thereof is connected to the wire 114 leading to the switch 105. The lower circuit will be as follows: From the conductor 77, the current will flow through the wires 84 and 85 to one end of each of the lower primary coils 23, thence through all of the turns of each coil to the low heat terminal posts 92, through the wires 94 and 93 to the low heat control switch 88, and back to the conductor 78 leading to the main line switch 79.

When the main line switch 79 and the two control switches are closed as above described all of the primary coils will be energized which will cause magnetic lines of force to flow through the sections of the magnetic core, as indicated by the dotted lines in Figure 7. As a result of the novel arrangement of the primary coils on the upper and lower sections 17 and 18 of the

magnetic core, two complete magnetic circuits will be generated in the core. The two magnetic circuits flowing through the magnetic core will cause an induced current to be built up in each of the secondary elements as is indicated by the arrows in Figure 8. On the left hand side of this figure, it will be noted that a rivet has been positioned between the upper and lower contact blocks 10 29 and 41. This rivet functions to complete the circuit through the secondary elements, as indicated by the arrows. Referring to this figure, it will be seen that the current flowing through the outer secondary elements, (which current is induced by the upper magnetic circuit shown in Figure 7), will flow from the upper horizontal leg 24 of the secondary element through the contact block 29, through the rivet, lower contact 15 block 41, the lower horizontal leg 25, and through the upright portion 26 of the outer secondary element and back to the horizontal leg 24, thereby completing the circuit. The current flowing through the above described 20 circuit is preferably of very high amperage, such for example, as 2000 amperes. As a result of the low current-carrying capacity of the rivet, it will immediately begin to heat, caused by the high resistance offered to the 25 current in flowing therethrough. When a rivet is heated in the manner above described, the upper or small end thereof usually becomes the hottest, as a result of the possibility of a poorer contact being obtained between the end of the rivet and the 30 contact block 29 than is obtained at the other end of the rivet, thereby causing greater resistance to the flow of current through that end of the rivet. It is, therefore, desirable 35 that means be provided whereby the body or grip portion of the rivet may be heated to an equal or relatively higher temperature than the small end thereof in order that the body or grip of the rivet will expand sufficiently, when headed over, to completely fill the rivet hole in which it is seated. Heating the lower or body portion of the rivet to a 40 higher temperature as above stated is readily accomplished by means of the lower primary windings 23. When the low heat switch 88 is closed as above described, an induced current will be built up in the inner secondary elements 36 and when the horizontally mounted contact block 43 is moved 45 into contact with the body of the rivet, which will also be in contact with one of the contact members 45, a complete circuit will be formed which will be as follows: through the upper horizontal leg 37 of the secondary 50 element 36, through the lower half of the rivet, contact block 41, lower horizontal leg 38 of the inner secondary element and back to the upper leg 37. By the closing of the 55 above circuit, the flow of current through the lower portion or body of the rivet will be

substantially increased, thereby causing that portion of the rivet to be heated to a much higher temperature than the upper end thereof.

In Figure 9, there is shown a rivet inserted in an aperture before being headed over. The shaded portion of the rivet here shown indicates the grip or body portion of the rivet which has been heated to a relatively higher degree of temperature than the upper end thereof. Thus when the upper end of the rivet has been headed over, as shown on the right-hand side of the figure, the body or grip portion thereof will be expanded sufficiently to completely fill the rivet hole, thereby positively preventing any leakage around the body of the rivet and also providing a very rigid and rugged connection between the two plates or members to be riveted together. When the plates have been riveted together as above described, the body or grip of the rivet will be substantially united with the walls of the aperture in which the rivet is mounted when a head is formed on the end thereof, caused by the expansion of the rivet body as a result of being heated to a relatively higher degree of temperature than the small end thereof.

From the foregoing, therefore, it will readily be seen that by the provision of the two interlocking heat control switch mechanisms, one preferably being provided for the upper and one for the lower primary coils, it will be possible to heat the body or grip portion of the rivet to a relatively higher temperature than the small end thereof. It will also be possible to heat the small end of the rivet to a higher degree of temperature than the body or grip portion thereof by decreasing the number of ampere turns of the lower primary coils 23 and by increasing the number of ampere turns of the upper primary coils 22. Such increasing and decreasing of the number of ampere turns of the primary coils is effected by the opening and closing of the heat control switches as above described. It is also to be understood that, if desired, either the upper or lower primary coils may be cut out of the circuit thereby causing only one set of contact blocks to function; that is, if the lower coils 23 are eliminated from the circuit, then current will be induced in the outer secondary elements only, while if the upper primary coils 22 are eliminated from the circuit, then the current will flow through the inner secondary elements 36 and through the lower portion of the rivet only, thereby heating only a portion of the rivet.

In Figure 1, the main line switch 79 is shown mounted on the left-hand side of the frame of the apparatus, while the heat control switches are shown mounted one on each side of the upper portion of the frame.

A lifting bail 116 may be provided on the frame whereby the apparatus may readily be lifted from one place to another by a suitable lifting means. The construction 5 of the novel secondary elements, as shown in Figure 3, may be varied from the particular construction shown. As here shown, it will be noted that the lower horizontal legs of each pair of secondary elements are 10 united by being integrally formed in the molding of the two elements, which are preferably constructed of copper or other suitable conductive material. When constructed as here shown the upper portion 15 of the inner secondary elements may be supported by the horizontal portion 26 of the outer secondary elements by such means as the straps 117, which have their ends suitably bolted to the two secondary elements 20 as shown in Figure 3. When such straps are used it is necessary that one end thereof be insulated from one of the secondary elements in order that there be no leakage of current from one secondary element to the 25 other. If desired, the secondary elements may also be independently constructed and mounted in their respective positions on the magnetic core, it being understood that the lower horizontal legs thereof need not be 30 electrically connected together as shown in the drawings. The purpose of constructing the secondary elements with their lower horizontal legs united, as shown, is to provide means whereby the contact faces 35 against which the contact blocks are mounted may be conveniently machined so that they will be in true alignment. If the secondary elements are independently constructed it will be necessary that they be 40 rigidly secured together in order that a good electrical connection may be obtained between the contact faces thereof and the contact blocks.

In Figure 3, the induced current flow 45 through the secondary elements is shown as flowing in one direction but it is to be understood, of course, that when using alternating current the flow of current through these elements will alternately flow 50 in both directions which is a well-known characteristic of alternating current flow.

The rivet heater shown in the accompanying drawings employs two upper and two lower primary coils but it is to be understood 55 that one or more of such coils may be used if desired without departing from the invention.

I claim as my invention:

1. A rivet supporting device for an electric riveting machine, comprising a first pair 60 of aligned contact and rivet-holding members slidably adjustably mounted, aligned and adapted to engage the opposite ends of a rivet, a second pair of contact and rivet-holding members similarly disposed and 65 adapted to engage a rivet at an intermediate point, a pivoted lever, connections between the lever and one member of said second pair of holding members, a spring for normally drawing the lever toward the 70 first mentioned pair of holding members, and a cam upon one of the first mentioned members adapted to throw said lever to move said second member to non-clamping position when the first member travels to 75 a similar position.

2. An apparatus of the class described, comprising primary coils having an electric circuit, secondary elements associated with the coils, through which separate induced 80 currents are established by the primary coils, one of the said secondary elements having movable contacts for engaging the ends of a rivet to be heated, with the rivet completing the circuit, the other secondary 85 element having movable contacts for engaging the shank of the rivet intermediate its ends, a cam and lever mechanism within the control of the operator for actuating said contacts to advance the same to rivet 90 contact and clamping positions, and electrical connections for the coils for energizing and controlling the same for generating a separate current for each secondary element.

3. An apparatus of the class described comprising primary coils having an electric circuit, secondary elements through which separate induced currents are established by the primary coils, one of said secondary elements having movable contacts for engaging the shank of a rivet or work intermediate its ends, and manually operable mechanism for simultaneously actuating said contacts for engaging, holding and causing 100 the rivet to complete both circuits.

4. A device of the class described comprising a magnetic core having parallel members, primary coils arranged on said parallel members, for inducing separate currents therein, an outer secondary element having upper and lower legs associating with the core, an inner secondary element also having upper and lower legs, said elements mounted upon and insulated from said 110 core and substantially insulated from one another, said core and coil adapted to induce a separate current in each element with the currents uni-directional, a rivet electrically connecting by its ends the upper 115 and lower legs of said outer secondary element and the lower leg of said inner secondary element, said rivet electrically connected at an intermediate point with the upper leg of said inner secondary element, adapting 120 the device to pass the two separately generated currents in the same direction through that portion of the rivet to be superheated.

5. A magnetic core having three parallel 130

members, the middle of the three forming a common return for current generated and passing through the other two, primary coils upon the outermost parallel members, 5 an outer secondary element having upper and lower legs, one leg between the intermediate and one outer parallel member and other leg below the other outer parallel member, adjustable contacts upon said legs 10 for engaging opposite ends of a rivet to hold the rivet as a circuit making member, an inner secondary element also having upper and lower spaced legs lying within, and aligned with said first mentioned legs, one 15 passing between the intermediate and outer parallel members, and the other adjacent and outside of the same outer parallel member, adjustable contacts upon the upper inner leg, adapted to electrically engage the 20 rivet at an intermediate point, and electrical connections for energizing and controlling the coils for simultaneously generating heating currents and causing the same to pass through both secondary elements, and through a rivet in the same direction, whereby one part of the rivet is 25 superheated by the additive effects of two distinct and separately induced currents.

6. A magnetic core having parallel members, primary coils arranged upon said parallel members, outer and inner secondary elements, each having upper and lower legs, respectively passing between, and lying at the outside of, said parallel members at 30 right angles thereto, insulated therefrom and substantially insulated from one another, the upper leg of the outer member and the lower legs of the inner and outer members having cooperable adjustable contacts for holding a rivet, and the upper inner leg of the secondary member having adjustable cooperable contacts adapted to engage a rivet at an intermediate point, and electrical connections for energizing and 35 controlling the coil for simultaneously generating separate currents, one in each secondary element, passing the same through the rivet with the currents flowing in the same direction whereby a portion of the 40 rivet is superheated.

7. An apparatus of the class described comprising a magnetic core having parallel members, coils upon the members adapted to generate two currents therein, outer and inner secondary elements on said magnetic core, each adapted to receive one of the currents induced by the core, each secondary element having upper and lower spaced legs, 45 movable contact blocks mounted upon the legs of said secondary elements adapted to clamp a rivet to be heated, and anti-friction means secured to said legs and adapted to yieldably hold said contact blocks in electrical contact with said legs.

8. An apparatus of the class described

comprising magnetic core having parallel members, outer and inner secondary elements on said magnetic core, each having upper and lower spaced legs, two sets of clamping contact members adjustable on the 50 legs, the sets angularly related, the first for engaging ends of a rivet and the second for engaging a rivet laterally at an intermediate point, a pivoted lever, connections between the lever of the last mentioned contact member for translating the same, means for yieldably urging the lever in contact direction, a cam upon one of the first mentioned contact members adapted to engage and swing the lever when moving to non-clamping position, for simultaneously correspondingly moving the lever-connected member and treadle means for translating the cam-carrying member.

9. A clamping and contact device of the class described including a first pair of aligned clamping and contact members, a second pair of similarly related clamping contact members, a pivoted lever connected with a contact member of the first pair, a 90 spring for urging the lever in clamping and contact direction, a cam on one member of said secondary pair of contact members, said lever engageable by the cam when moving from clamping position, whereby after one 95 member moves to clamping position the lever acts to simultaneously move the other to and maintain it in a similar position.

10. A magnetic core having parallel members, secondary elements traversing said core 100 at right angles thereto and insulated therefrom, providing upper lower, and intermediate legs, and contact devices one upon each upper and lower leg adjustable for engaging opposite ends of a rivet, clamping and contact devices upon said intermediate leg adjustable to engage a rivet at an intermediate point, and primary coils upon said core arranged connected and electrically controllable, and adapted to induce two distinct heating currents in the secondary elements, with the secondary currents uni-directional.

11. In a device of the class described, a magnetic core having three parallel members connected together at opposite ends, two U-shaped secondary elements, outer and inner, arranged in nested relation, each providing upper and lower legs, one leg of the outer member disposed between, crosswise and insulated from two of the parallel members of the core, and the other extending crosswise at, and insulated from the outer side of the core, one leg of the inner element disposed between, crosswise and insulated from the other two parallel core members, and the outer leg of the inner element disposed at the outer side of the core insulated therefrom, spaced from and attached only at its outer end to the corresponding 115 120 125 130

end of the other element, clamping elements upon the projecting ends of the elements adapted respectively to contact a rivet at its ends and at an intermediate portion, 5 coils upon the core, and electrical means for energizing the coils to pass a separate current through each secondary element, with the current uni-directional, through a rivet clamped completing the circuit therebe- 10 tween.

12. A work clamping device for an electric riveting-heating machine, comprising a first pair of aligned contact and riveting-holding members slidably adjustable, a second 15 pair of contact and rivet-holding members slidably adjustable and adapted to engage a rivet at a point intermediate its ends, a pivoted lever, a link connecting said lever with one of said members, a spring for normally drawing the lever toward the first mentioned members and a cam upon one member of the first mentioned pair of members adapted to engage and retract the lever when the members are retracted from clamping 20 position, and further adapted to release the lever to obtain clamping action of the other member when the first-mentioned members travel to clamping position.

13. A device of the class described comprising a magnetic core having parallel members, primary coils arranged on said parallel members, electrical means for controlling the coils for developing two currents in the core, the currents having a common 30 return in the same direction in the core, an outer secondary element having upper and lower legs, an inner secondary element having upper and lower legs, said elements mounted upon and insulated from the core 35 and substantially from one another, and each arranged and adapted for receiving a separate current induced by the core with the currents uni-directional, and having a common return through the lower elements, 40 and a rivet electrically connecting at its ends the upper and lower legs of said outer secondary element and the lower leg of the inner secondary element, the upper leg of the inner secondary element connected with,

and adapted to pass a second current 50 through the rivet from an intermediate portion, to superheat that part of the rivet through which both uni-directional currents pass.

14. A device of the class described, comprising a magnetic core frame providing three parallel members spaced and connected at their ends with the intermediate member as a common return for a current set up by the core, outer and inner U-shaped 60 secondary elements disposed one within the other and mounted upon the core crosswise thereof, having corresponding legs at the outer side of the core connected to provide a common current return, with the other 65 legs of the inner and outer element respectively passing between the intermediate member and different outer members, coils upon the outer members of the core arranged for generating currents having the same 70 direction in the common return or intermediate member, clamping means upon the outermost legs of the secondary elements for holding a rivet in position for passing a current lengthwise therethrough, and means 75 upon the central or innermost leg of the inner secondary member for making electrical contact with the rivet at an intermediate point, whereby separate currents are induced in each secondary element with the 80 current flowing in the same direction for obtaining additive heating effects through a portion of a rivet for superheating that portion.

15. A magnetic core having parallel members, secondary elements traversing said core at right angles thereto and insulated therefrom and providing upper, lower and intermediate legs, and primary coils upon said core arranged and connected and electrically 85 controllable and adapted to induce two distinct heating currents in the secondary elements, with the secondary currents uni-directional.

In witness whereof, I have hereunto set 90 my hand this 1st day of December, 1924.

JOHN E. SEDERHOLM.
